UNITED STATES PATENT OFFICE.

ALBERT ENNIS HENDERSON, OF TORONTO, ONTARIO, CANADA.

VALVE BASE FOR PNEUMATIC TIRES.

Application filed January 27, 1917. Serial No. 144,911.

My invention relates to improvements in valve bases for inner tubes in which the tube is provided with strengthening fabric so arranged as to permit the insertion of the button of the valve stem from without, at the same time ensuring the proximity of the fabric surrounding the valve stem to the reduced shoulder of the stem, so as to permit the same to be securely clamped by the 10 washers of the valve stem.

In my Patent No. 1,160,168, dated the 16th day of November 1915, I duly protected that form of valve base in which the fabric is slotted before being imbedded in the tube 15 in such manner that the rubber of the tube fills the slot and not only permits the expansion of the slotted fabric, but upon the insertion of the stem pulls the fabric into normal position adjacent to the reduced 20 shoulder of the stem.

In this particular patent I have not confined myself to any arrangement of the slotted fabric, but any form in which the slot in the fabric is different in its outline 25 to the opening punched within the slot in the rubber of the tube for receiving the button of the valve stem is duly covered by this patent.

In my present application the fabric 30 strips are arranged in such form that they do not require to be slotted, but the relation of the several strips of fabric to each other is such as to provide for the necessary expansion of the base in order to admit the 35 button of the valve stem.

The objects of my improvements are:—

First. To provide a simple and convenient 40 method of inserting the fabric for the valve base.

Second. To provide means whereby the valve base may be yieldingly connected with 45 protecting strips on the rim side of the tube.

Third. To so arrange the fabric in the 50 base that the stem may be readily inserted from without.

Fourth. To so surround the various portions of the fabric of the base with the rubber of the tube as to permit the fabric adjacent to the valve stem opening to elastically expand to permit the inserting of the 55 valve button.

Fifth. To so arrange the rubber of the tube and the fabric that in its normal condition after the stem is inserted the fabric of 60 the base will be adjacent to the reduced portion of the valve stem.

Referring to the accompanying drawings which are made a part hereof and on which similar reference characters indicate similar parts,

Figure 1 is a plan view of a portion of the tube at the base showing the relation of the fabric of the tube,

Figure 2, a fragmentary transverse sectional view showing radially the relation of 65 the strips comprising the valve base, on line 2—2 of Figure 1,

Figure 3, a modified form of the construction shown in Figure 1,

Figure 4, a fragmentary transverse section 70 of the tube showing the relation of the parts in figure 3, taken on line 4—4 of said figure,

Figure 5, a further modification of the base as shown in Figure 1, and

Figure 6, a fragmentary sectional transverse view of Figure 5, taken on line 6—6 75 of said figure.

In Figure 1 I show a section of a tube 10, having the rim-side-reinforcing fabric strip 15 broken transversely and separated from the adjacent end of the strip 15' by the rubber of the tube, said strips 15 and 15' being superimposed upon the patches 20 and 20', and separated radially from the 80 same by the film of rubber 21, and in overlapping relation transversely and longitudinally with the said patches 20 and 20'. The strip of rubber 22, extending longitudinally between the adjacent sides of the patches 20 and 20' permits transverse expansion of the 85 fabric of the tube in relation to the strips of fabric 15 and 15'. Thus it will be seen that the various sections of fabric comprising the base of the tube are each enveloped in the rubber of the tube and separated from each other. A fabric 24 is located over or outwardly of the spaced ends of patches 15, 15', this patch having an opening 25 for the valve, coinciding with the spaces between the adjacent edges of patches 20, 20' and 90 strips or strip ends 15, 15'.

In Figure 2 is shown the transverse relation of the parts 20 and 20', 15' and 24 in the transverse radial relation to each other, thus radially as well as transversely and 95 longitudinally the strips are all separated from each other.

The rubber of the tube is cut away showing the patch 24 having the slot 25.

In Figure 3 I have shown the patch 24' 110 broken transversely at 31 superimposed upon the strip 15'', which is provided with

an opening 32 disposed longitudinally of the tube, said strip 15" being superimposed upon the patches 20 and 20' and separated therefrom by a film of rubber 21 of the tube.

5 In Figure 4 is shown the transverse relation of the several portions of the base referred to in Figure 3.

In Figure 5 I show the patch 24" provided with an opening 37 superimposed upon the strip 15" provided with an opening 34 and separated radially by the film 35 from the patch 20", which is provided with an opening 33, the position of the elongated openings 34 and 33 being parallel 10 with the bias formation of the fabric in strips 15 and 36, as indicated fragmentarily in Figure 5.

In Figure 6 is shown in section the transverse relation of the fabric shown in Figure 5.

It will thus be seen that I have provided a variety of forms in which the rubber of the tube envelopes in various constructions the fabric of the valve base in such form 25 that an elastic character is given to the base such as will permit the insertion of the but-

ton of the valve stem from without, and such as will insure the proximity of the fabric imbedded in the tube to the reduced shoulder adjacent to the button of the stem.

I have provided in all the several views means whereby the valve base may be overlappingly connected with any protecting strips on the rim side of the tube.

I do not confine myself to the construction shown in the several figures described in the specifications, as certain variations may be made in the form of the construction embodying the general principles of my invention without departing from the spirit of my invention, as set forth in the claim.

I claim:

A tube for pneumatic tires, said tube having rim side re-inforcing fabric embedded therein, and also having fabric patches embedded therein inwardly and outwardly from the rim side re-inforcing fabric in a radial direction to form a valve base, substantially as set forth.

In testimony whereof I have hereunto affixed my signature.

ALBERT ENNIS HENDERSON.
